(57) **ABSTRACT**

A new cherry tree variety suitable for use as rootstock.

7 Drawing Sheets

Specification includes a Sequence Listing.

1

Botanical designation: The present invention relates to a new (*Prunus cerasus* L. x *Prunus canescens* Bois) open-pollinated cherry tree variety.

Variety denomination: The new plant has the varietal denomination 'Clinton'.

BACKGROUND OF THE INVENTION

This invention relates to a new and distinct variety cherry tree. In the field of plant genetics, researchers conduct an extensive and continuing plant-breeding program including the organization and asexual reproduction of orchard trees, and of which plums, peaches, nectarines, apricots, cherries, almonds and interspecifics are exemplary. It was against this background of activities that the present variety of cherry tree was originated and asexually reproduced in our experimental orchard.

PRIOR VARIETIES

Among the existing varieties of cherry trees, which are known to us, and mentioned herein, 'Hedelfingen' (not patented); 'Montmorency' (not patented); 'Bing' (not patented); and Cherry rootstock GI 148/2 (U.S. Plant Pat. No. 9,622); and Cherry rootstock GI 148/1 (U.S. Plant Pat. No. 8,954).

ORIGIN OF THE VARIETY

Open-pollinated 'GiSelA® 5' (GI 148/2), seeds were planted in Clarksville, Mich. Seedlings were selected as

2

candidate rootstocks, based on overall plant health, virus tolerance (Bromoviridae Ilarvirus species Prune Dwarf Virus and Bromoviridae Ilarvirus species *Prunus* Necrotic Ringspot Virus), and rooting capabilities. Candidate rootstocks produced by asexual propagation were grafted with 'Hedelfingen' scion and planted in Clarksville, Mich. Further rootstock selection occurred on the basis of scion qualities to include precocity (early flowering and fruiting beginning the second year after planting) and reduced tree stature measured as trunk cross-sectional area. 'Clinton' was asexually reproduced through conventional softwood cutting methods, and grafted and planted with 'Bing' scion. The 'Bing' trees grafted on the 'Clinton' rootstock were planted in Prosser, Wash. and evaluated for trunk cross-sectional area, tree height, growth habit, flowers per node, crop yield, cropping efficiency, and fruit weight, among other traits. 10 15 Cherry tree 'Clinton' was selected from this trial.

ASEXUAL REPRODUCTION OF VARIETY

20 Asexual reproduction of the 'Clinton' cherry rootstock has been achieved using the mother plant to obtain rooted liners using conventional softwood cutting procedures, and through meristem culture with commercial nurseries. Initially, liners were propagated from softwood cuttings in commercial greenhouses. A subset of these liners was used to establish a mother block in Clarksville, Mich. The remaining liners were sent to a nursery to make test trees of 'Clinton' that were budded with the scion 'Hedelfingen'. The 25

resulting trees were planted in a trial in Clarksville, Mich. A second set of liners was propagated from softwood cuttings in commercial greenhouses. These 'Clinton' liners were budded with 'Bing' scion to make trees for a trial in Prosser, Wash. A nursery established meristem cultures of 'Clinton', and using the plantlets produced they increased the liner number of 'Clinton'. These liners were used to make trees with 'Montmorency' scion for a trial in Traverse City, Mich. The living tissues (i.e. leaves, stems, buds, flowers and fruits) of the original mother block plants were observed to be identical to secondary and tertiary vegetatively propagated plants.

STATEMENT OF STABILITY

Asexual propagation as described has demonstrated that the combination of traits that characterize this tree are fixed and remain true to type through at least two successive propagation cycles.

SUMMARY OF THE INVENTION

'Clinton' is particularly useful as a rootstock. The variety results in dwarf trees with a significantly smaller canopy size than traditional non-dwarfing rootstocks. When this variety is used as a rootstock for sweet cherry, the fruit can be harvested without using ladders.

When used as a rootstock for sour cherry the fruit can be harvested by an over the row harvester that can move continuously down the row instead of being harvested by a trunk shaking machine that harvests each tree individually. The variety of the invention also has favorable precocity, which results in a scion variety having flower buds and fruit beginning in years two and three rather than years five or six when traditional rootstocks are used.

'Clinton' was selected as a cherry rootstock on the basis of its scion trunk cross-sectional area (TCSA), tree height, growth habit, flowers per node, crop yield, cropping efficiency, and fruit weight, among other traits, in two experimental field trials. Scion trees grafted onto this rootstock showed significant reduction in TCSA compared to 'GiSelA® 6' (GI 148/1) and a TCSA similar to 'GiSelA® 5' (GI 148/2). 'Clinton' is suitable for standard nursery propagation practices for uniform liner production. 'Clinton' can be distinguished from its parents by the use of Simple Sequence Repeat DNA markers. With primer pair PceGA59, 'Clinton' is distinguished from its parent, 'GiSelA® 5' (GI 148/2), by the presence of the 189-base pair (bp) allele, with the primer pair PruG4RS, 'Clinton' is distinguished from its parent, 'GiSelA® 5' (GI 148/2), by the presence of the 172 and 196 bp alleles.

COMPARISON WITH PARENTS

The new cherry variety may be distinguished from its seed parent, 'GiSelA® 5' (GI 148/2) in anthocyanin color of the Apex, the leaf blade angle at apex, using the PceGA59 primer pair—the presence of the 189 bp allele; and using the PruG4RS primer pair the presence of the 172 and 196 bp alleles. The pollen parent is unknown.

BRIEF DESCRIPTION OF PHOTOGRAPHS

The accompanying photographs display flowers, leaves, leaves image 2, and fruits from a self-rooted mother block tree at Clarksville, Mich. planted in 2005.

FIG. 1 is a photograph showing the flowers of CLINTON (May 2014);

FIG. 2 is a photograph of two leaves from CLINTON (July 2016);

FIG. 3 is a photograph of five leaves of CLINTON with a ruler (July 2016);

FIG. 4 is a photograph of cherries from CLINTON (July 2013);

FIG. 5 is a photograph of the young tree of CLINTON (July 2016);

FIG. 6 is a photograph of the flowers on the tree of CLINTON (May 2014);

FIGS. 7A and 7B are photographs of the cherry tree of CLINTON before and after thinning (2012).

DESCRIPTION OF THE NEW VARIETY

The following is a detailed botanical description of the new variety of cherry tree, its flowers, foliage and fruit, as based on observations of various aged specimens grown at Clarksville, Mich. with color in accordance with The Royal Horticultural Society Colour Chart (R.H.S.), 2001 edition. Measurement details:

Flowers:

Inflorescence height.—Measured from where the flower cluster attaches to the branch to the most distal floral part.

Flower diameter.—Measured across the petals in mm.

Flower length.—Measured from the bottom of the pedicel to the most distal flower point (mm).

Pedicel.—The stem of an individual flower. It is measured from the attachment in the bud to the start of the perianth.

Peduncle.—A stalk supporting an inflorescence. In these selections, the cherry flowers within a flower bud all start at the same base and they the stalk separates into individual pedicels supporting each flower.

Anther color.—Before the anther's dehisce, when they are still bright yellow and plump.

Anther length.—Measured for the longest anther measured from the top of the perianth tube.

Style.—Measured above the swelled ovary.

Tree.—Height: Approx. 8 ft. Diameter: Approx. 10 ft. Vigor: Weak. Branching habit: Spreading. Branching: Strong. Hardiness: Cold Tolerant. Plant—flowers: present. Scion compatibility confirmed: Hedelfingen, Bing, Montmorency.

Stem (trunk).—Strength: medium. Texture: rough.

Color: grey brown (RHS 200A). A comparison of the stems of 'Clinton' and 'GiSelA® 6' (GI 148/1) is provided in Table 1 below:

TABLE 1

Botanical description	'Clinton'	'GiSelA® 6' (GI 148/1)
Stem strength	medium	medium
Stem texture	rough	rough
Stem color	grey brown	grey brown

One year old shoot.—Thickness: thin. Length of internode (middle third of shoot — mean of 10): 4.0 cm

(2.9-5.2). Pubescence (upper third): present. Number of lenticels: 6. Anthocyanin coloration of apex: medium. Position of vegetative bud in relation to shoot: slightly-markedly held out. Shape of apex of vegetative bud: obtuse. Branching: medium.

Leaves.—Mature leaf arrangement: alternate. Intensity of anthocyanin coloration of young leaf (during rapid growth): medium. Leaf blade shape: ovate. Leaf blade: ratio length to width: 1.6. Leaf length-blade only (cm): 8.1. Leaf width (cm): 4.9. Leaf blade angle of apex (excluding tip): right-angled. Leaf blade shape of base: obtuse. Leaf blade shape of apex (e.g., acute): acute. Leaf blade: incisions of margin: only serrate. Leaf blade: depth of incisions of margin: medium. Leaf blade color of upper side: light green (RHS 137B). Leaf blade: glossiness of upper side: medium. Leaf blade: pubescence of lower side of apex: medium. Petiole: presence of pubescence of upper side: present. Petiole: intensity of pubescence of upper side: medium. Petiole: depth of groove: shallow. Leaf ratio length of leaf blade/length of petiole: 5.1. Leaf: presence of nectaries: present. Varieties with nectaries only: Leaf — predominant number of nectaries: two. Leaf: position of nectaries: base of leaf blade. Nectary shape: reniform. Upper surface color (RHS): 137B. Leaf upper surface texture/pubescence: smooth. Leaf upper surface venation color (RHS): 138A. Lower surface color (RHS): 137C. Leaf lower surface texture/pubescence: medium pubescence. Leaf lower surface venation color (RHS): 138C. Leaf stipule frequency: present. Leaf stipule length (mm): 10. Leaf stipule width (mm): 2.5. Leaf stipule shape: pointed. Leaf stipule margin: serrated. Leaf petiole length (mm): 13. Leaf petiole diameter (mm): 1.5. Leaf petiole color (RHS): 138B and 59A. A comparison of the leaves of 'Clinton' and 'GiSelA® 6' (GI 148/1) is provided in Table 2 below:

TABLE 2

Botanical description	'Clinton'	'GiSelA® 6' (GI 148/1)
Mature leaf arrangement	alternate	alternate
Leaf length-blade only (cm)	8.1	8.7
Leaf width (cm)	4.9	5.4
Laminae apex	acute	acute
Leaf upper surface texture/pubescence	smooth	smooth
Leaf upper surface venation color (RHS)	138A	138A
Leaf lower surface texture/pubescence	medium pubescence	medium pubescence
Leaf lower surface venation color (RHS)	138C	138C
Leaf stipule frequency	present	present
Leaf stipule length (mm)	10	6
Leaf stipule width (mm)	2.5	2

TABLE 2-continued

Botanical description	'Clinton'	'GiSelA® 6' (GI 148/1)
Leaf stipule shape	pointed	pointed
Leaf stipule margin	serrated	serrated
Leaf petiole length (mm)	13	11
Leaf petiole diameter (mm)	1.5	1.6
Leaf petiole color (RHS)	138B and 59A	138B and 59A

Flowers.—Flowers per cluster: 2 to 3. Fragrance: none. Bloom date (50%): Apr. 29, 2016. Inflorescence height (cm): 4.2. Inflorescence diameter (cm): 4.6. Flower diameter (mm): 32. Flower length (mm): 33. Petal number per flower: 4 or 5. Petal arrangement: flat whorl. Petal length (mm): 11.3. Petal width (mm): 9.5. Petal shape: oval/round. Petal apex: round. Petal margin: smooth. Petal texture: smooth (both upper and lower sides). Petal color when fully opened — upper surface (RHS): 155D. Petal color when fully opened — lower surface (RHS): 155D. Sepal number: 4 or 5. Sepal length (mm): 4.8. Sepal width (mm): 3. Sepal shape: triangle. Sepal apex: pointed. Sepal margin: serrated. Sepal texture: smooth (on upper side and pubescent on lower side). Sepal color upper (RHS): 138B. Sepal color lower (RHS): 59A with some 138B. Flower pedicel length (mm): 19. Flower pedicel diameter (mm): 1. Flower pedicel angle (degrees): 30. Flower pedicel texture: smooth. Flower pedicel color (RHS): 59A to 138B. Flower peduncle length (mm): 1. Flower peduncle diameter (mm): 2. Flower peduncle texture: smooth. Flower peduncle color (RHS): 138B. Pistils: number per flower: 1. Pistil length (mm): 7.5. Pistil color (RHS): 149B. Style length (mm): 9. Style color (RHS): 138C. Stigma shape: round/indented. Stigma color (RHS): 138B. Stamens: number per flower: 18 to 24. Longest filament length (mm): 8. Filament color (RHS): 155D. Longest anther length (mm): 9. Anther color (RHS): 20B. Pollen color (RHS): 17C. Pollen amount: moderate. A comparison of the flowers of 'Clinton' and 'GiSelA® 6' (GI 148/1) is provided in Table 3 below:

TABLE 3

Botanical description	'Clinton'	'GiSelA® 6' (GI 148/1)
Flower fragrance	none	none
Entire flower bloom period	—	—
Individual flower bloom period	—	—
Inflorescence height (cm)	4.2	3.5
Inflorescence diameter (cm)	4.6	3/7
Flower diameter (mm)	32	24
Flower length (mm)	33	31
Petal arrangement	flat whorl	flat whorl
Petal shape	oval/round	oval/round
Petal apex	Round	Round
Petal margin	smooth	smooth
Petal texture	smooth	smooth
Petal color - upper surface	155D	155D

TABLE 3-continued

Botanical description	'Clinton'	'GiSelA® 6' (GI 148/1)
Petal color - lower surface	155D	155D
Sepal shape	triangle	triangle
Sepal apex	pointed	pointed
Sepal margin	serrated	serrated
Sepal texture	smooth	smooth
Sepal color (upper)	138B	138B
Sepal color (lower)	59A with some 138B	59A with some 138B
Flower pedicel length (mm)	19	15
Flower pedicel diameter (mm)	1	1
Flower pedicel angle (degrees)	30	30
Flower pedicel texture	smooth	smooth
Flower pedicel color	59A to 138B	59A to 138B
Flower peduncle length (mm)	1	8
Flower peduncle diameter (mm)	2	2
Flower peduncle texture	smooth	smooth
Flower peduncle color	138B	138B
Number of pistils per flower	1	1
Style length (mm)	9	8
Style color	138C	138C

Anther length (mm)	8	7
Anther color (RHS)	9B	9B
Pollen color (RHS)	17C	17C

Fruit.—Mature fruit shape: flat-round. Mature fruit height (mm): 16.3. Mature fruit width 1 (mm): 17.2. Mature fruit width 2 (mm): 18.8. Mature fruit ratio height/width 2: 0.87. Mature fruit weight (g): 3.6. Mature fruit flesh taste: sour. Mature fruit skin color (RHS): 45A. Mature fruit flesh color (RHS): 31C. Stone color (RHS): 164D. Stone shape: oval. Stone number: 1. Stone height (mm): 8.6. Stone width 1 (mm): 8.4. Stone width 2 (mm): 6.6. Stone ratio height/width 2: 1.31. Stone weight (g): 0.27. Fruit stem length (mm): 32. A comparison of the fruit of 'Clinton' and 'GiSelA® 6' (GI 148/1) is provided in Table 4 below:

TABLE 4

Botanical description	'Clinton'	'GiSelA® 6' (GI 148/1)
Mature fruit shape	flat-round	round
Mature fruit flesh taste	sour	sweet-sour
Mature fruit flesh color (RHS)	31C	23C
Mature fruit skin color	45A	45A
Stone color (RHS)	164D	164D
Stone shape	oval	oval
Stone number	1	1

Simple Sequence Repeat (SSR) Materials and Methods

The use of clonally propagated *Prunus* sp. rootstocks in cherry production is increasing as these rootstocks provide reduced tree size and precocity. DNA markers that differentiate rootstocks are an important tool to verify identity among these rootstocks during the vegetative propagation stage. The simple sequence repeat (SSR) marker PceGA59

was previously determined to uniquely distinguish the commercially available GiSelA® (GI 148/2 and GI 148/1) rootstocks (Struss et al. 2002).

A targeted approach was used to develop a second SSR that was capable of providing differentiation of the rootstock selections of the invention and others by the inventors. The approach used was based on the ability to obtain genome-wide SNP (Single Nucleotide Polymorphism) data using the Illumina Infinium® cherry SNP array (Peace et al. 2012). An analysis of genome-wide SNP data for the rootstocks resulted in the identification of a genomic region on linkage group 4 that was likely to differ among the MSU rootstocks.

Using the peach genome sequence, an SSR marker was designed to target this region. This SSR marker, termed PruG4RS, successfully differentiated the MSU rootstocks. The development of PruG4RS and its combined use with PceGA59 has successfully circumvented the limitations of each individual marker and proven effective for use as a "quality control" DNA diagnostic tool for the commercial 'GiSelA®' (GI 148/2 and GI 148/1) rootstocks as well as the MSU breeding program rootstock selections.

SSR Markers Used

Fingerprinting was performed using two simple sequence repeat (SSR) markers: PceGA59 and PruG4RS. The forward and reverse primers sequences for these two SSR markers are as follows:

TABLE 5

Primer name	Primer sequence 5' → 3'
PceGA59_redesigned_F	TGAACCCCTCTACAAATTTC
PceGA59_redesigned_R	GACTGTAGAACCCAAAGAACG
PruG4RS - F	TCAGAAAAGAAATTGCAACGGG
PruG4RS - R	CTT AGT GGT CTA GTC TGC ATG C

The first primer pair, PceGA59, was published in Struss et al. (2002). However, the primer sequence reflects the addition of GC clamps. Based on genetic data for the MSU cherry rootstocks we designed a second primer, PruG4RS (Andersen et al. 2015)

Plant Material Used and DNA Extraction

Cherry DNA was extracted from young unfolded leaf blades using the procedure of Edge-Garza et al. (2014). Polymerase Chain Reaction (PCR)

PCR amplification was performed for the two SSRs using the following conditions: 94° C. for 5 min followed by 9 cycles of 94° C. for 30 s, 60° C. for 45 s (-1° C. per cycle), 72° C. for 1 min and then 24 cycles of 94° C. for 30 s, 55° C. for 45 s, 72° C. for 1 min with an elongation step of 72° C. for 5 min.

Gel Electrophoresis and Fragment Visualization

The PCR products were visualized by electrophoresis on a 6% denaturing polyacrylamide gel in a 50 cm Sequi-Gen GT vertical sequencing apparatus (Bio-Rad Laboratories, Hercules, Calif.) for 2.5 hours at 70 watts with 1× TBE buffer. Following electrophoresis, the gels were stained with the Silver Sequence DNA Sequencing System (Promega Corporation, Madison, Wis.) and dried for 24 hours. DNA fragment sizes were scored visually using 10 and 50 base pair ladders (Invitrogen Corporation, Carlsbad, Calif.).
